PLATE-SHAPED INDUCTOR FOR INDUCTIVE HIGH-FREQUENCY HEATING

Dirk Christiaan van Iperen, Eindhoven, Netherlands, assignor, by mesne assignments, to North American Philips Company, Inc., New York, N. Y., a corporation of Delaware

Application August 3, 1953, Serial No. 371,896

Claims priority, application Netherlands October 16, 1952

4 Claims. (Cl. 219—10.79)

The invention relates to a plate-shaped inductor for inductive high-frequency heating which is characterized in that at least one of the sides forming the boundaries of the working opening is provided with an aperture, of which the edge adjacent the working opening is at least partly substantially parallel to the edge of the working opening in situ.

This has the advantage that at the said area the electromagnetic field need not pass through the electrically conductive material of the inductor, so that the losses are reduced and a desirable stronger heating is obtained at that area.

According to a further feature of the invention the plate-shaped inductor is provided with at least two apertures one on each side of the insulation between the supply points of the inductor, preferably in symmetrical arrangement.

The disadvantage inherent in the use of the conventional plate-shaped inductors in that the heating of the work piece in the proximity of the insulation is frequently insufficient to meet the requirements is thus mitigated.

In order that the invention may be readily carried into effect, it will now be described with reference to the accompanying drawing.

Referring to Fig. 1, the plate-shaped inductor 1, having a working opening 2, is provided with an aperture 3 in one of the sides, the edge 4 of the aperture on the side of the working opening 2 being parallel to the edge 5 of the working opening in situ. Thus the inductive electromagnetic field is capable of completing itself unhindered through the aperture 3 about the uniformly wide strip 6 of the inductor 1, as is indicated by arrows, since the resistance of the material of the inductor is absent at this area. If desired, the aperture may be filled out more or less by a material having high permeability, for example, a ferrite, so that the field may be further intensified.

2

The inductor shown in Fig. 1 is furthermore provided with two additional apertures 8 and 9 symmetrically one on each side of the insulation 7, for example, an air gap, the edges 10 and 11 of these apertures being parallel to the inner wall 12 of the inductor. Thus also the heating of the work piece at this area is improved, so that the harmful effect of the air gap 7 may be more or less compensated. Moreover, the current is thus compelled to flow more along the corners 13, so that the length of the path is increased along the edge 12.

Referring to Fig. 2, the two apertures 14 and 15 open in the outer edges 16 and 17 of the inductor, so that the full current is compelled to flow along the corners 13 and an increased effect is obtained. An additional aperture 18 is provided on the side opposite the work piece in order to enhance the heating.

Such inductors are of particular importance for high-frequency soldering of iron tins and the like.

What is claimed is:

1. A C-shaped, plate-like inductor for high frequency heating defining a working aperture and having an air gap between the ends of said inductor, an elongated opening completely through and completely surrounded by the material of said inductor adjacent said working aperture having at least one bounding edge thereof substantially parallel to the adjacent edge of said working aperture.

2. A C-shaped, plate-like inductor as set forth in claim 1 wherein a material having a high permeability is contained in said elongated opening.

3. A C-shaped, plate-like inductor as set forth in claim 1 further including a pair of apertures in the ends of said inductor adjacent to said air gap.

4. A C-shaped, plate-like inductor as set forth in claim 1 further comprising at least one recess in the outer marginal edge of said inductor and in a position adjacent said air gap.
